CLAIM

The ornamental design for a spinning fish lure, as shown.

DESCRIPTION

FIG. 1 is a perspective view of a spinning fish lure showing my new design, in accordance with a first embodiment of the present invention;

FIG. 2 is a front elevational view of the design of FIG. 1;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof;

FIG. 8 is a perspective view of a spinning fish lure showing my new design, in accordance with a second embodiment of the present invention;

FIG. 9 is a front elevational view of the design of FIG. 8;

FIG. 10 is a left side elevational view thereof;

FIG. 11 is a right side elevational view thereof;

FIG. 12 is a rear elevational view thereof;

FIG. 13 is a top plan view thereof; and,

FIG. 14 is a bottom plan view thereof.
